CLAIM

The ornamental design for a pool lighting adapter plate, as shown and described.

DESCRIPTION

FIG. 1 Is a top view of a pool lighting adapter plating showing a new design;

FIG. 2 is a front view thereof;

FIG. 3 is a top view thereof;

FIG. 4 is a bottom view thereof;

FIG. 5 is a bottom, front, and left side perspective view thereof;

FIG. 6 is a bottom, front, and right side perspective view thereof; and,

FIG. 7 is a sectional view thereof taken along line 7-7 in FIG. 1.

The broken line shown in FIG. 1 represents the viewing plane in which the sectional view of FIG. 7 is taken from and forms no part of the claimed design.
